UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

ACETYLENE-LAMP.

1,295,744.

Specification of Letters Patent.

Patented Feb. 25, 1919.

Application filed September 3, 1918. Serial No. 252,298.

To all whom it may concern:

Be it known that I, AUGIE L. HANSEN, a citizen of the United States, and a resident of Evanston, in the county of Cook and State of Illinois, have invented certain new and useful Improvements in Acetylene-Lamps, of which the following is a specification.

My invention relates to gas lamps and particularly to improved pyrophoric ignition mechanism therefor which is of special utility in connection with miners' acetylene cap lamps.

The main object of the invention is to provide pyrophoric ignition mechanism whose location is such with reference to the gas tip that when operated to produce sparks breaking up of the otherwise thin solid gas stream will be accomplished in order to afford greater volume of gas for contact with the sparks so that ignition of the lamp is assured. Another object of the invention is to provide such construction as will enable the ignition mechanism to be readily applied to existing types of lamps.

A lamp to which my improved sparking mechanism is applied is illustrated on the accompanying drawing, in which—

Figure 1 is a front elevational view of the lamp, and

Fig. 2 is a sectional view on plane 2—2, Fig. 1.

The lamp shown is a miner's cap lamp comprising the water container 5 and the detachable carbide cup 6, the water tube 7 leading from the water container to the carbide cup and the flow being controlled by means of the valve stem 8 extending through the tube. The concave reflector 9 forms the front wall of the water container and the gas tube 10 communicates at its lower end with the carbide cup and extends at its upper end axially through the reflector and receives the gas tip 11 and the gas outlet 12. Close to and at one side of the tip the reflector has the opening 13 through which the barrel 14 is projected to extend into the water container. Threading into the front end of the barrel is the plug 15 which has the passageway 16 therethrough for the bar 17 whose upper surface is roughened or serrated. At the rear end of the bar is the head 18 between which and the plug 15 the compression spring 19 is confined, which spring tends to forcibly draw the bar back

after outward shifting thereof. A link 20 has pivotal connection with the outer end of the bar and its other end terminates in a ball 21, this link serving as a finger grip for pulling out the bar. A slot 22 extends vertically through the plug 15 from the top thereof and has its opposed sides concave to form a guideway for a cartridge 23 of pyrophoric material. A coiled spring 24 encircles the outer end of the gas tube 10, the end 25 of the spring being anchored against the underside of the plug and the upper end 26 of the spring extending through the slot 22 to press downwardly on the cartridge to thereby yieldingly hold the cartridge against the serrated upper surface of the bar 17 so that when the bar is shifted sparks will be produced. The barrel 14 is at an angle with the axis of the tip so that when the bar is drawn outwardly the incandescent particles torn from the pyrophoric cartridge will be projected toward the flame jet issuing from the tip along the axis of the reflector.

To draw the bar outwardly the link 20 is grasped between the thumb and finger as illustrated in Fig. 2, the thumb being then close to and in front of the tip so that the thin solid gas stream will, upon striking the thumb, be broken up and the gas deflected and dispersed laterally into the concave reflector space, the gas thus offering greater volume for ignition thereof by the sparks. Sparks generated upon shifting of the bar will therefore always encounter gas and the resulting flame transmitted to the tip. The bar can be either quickly pulled out to project the sparks or it can be drawn out and then suddenly released so that it will be quickly drawn back by the spring 19, the resulting sparks being then deflected laterally through the slot 22 into the gas. If the gas is not ignited when the bar is drawn out it will be ignited when the bar is jerked in. The smooth ball 21 enables a firm grip to be had on the link and the bar can be quickly released by withdrawing the pressure of the fingers on the link and ball.

The sparking mechanism is of simple construction and can be readily applied to the existing types of lamps.

I do not, of course, desire to be limited to the exact construction, arrangement and operation shown and described as changes and modifications are no doubt possible.

which would still come within the scope of the invention.

I claim as follows:

1. The combination with a gas tip, of a barrel secured alongside thereof, a plug in the front end of said barrel adjacent the tip outlet, a serrated bar extending through said plug into said barrel, said plug having a transverse pocket, a cartridge of pyrophoric material in said pocket for engaging with said serrated bar, a spring pressing said cartridge against said bar, and a finger grip extension at the outer end of said bar, said finger grip being in such position with reference to the tip outlet that when grasped by the fingers the gas will strike the fingers and be deflected laterally toward the stream of sparks caused when said bar is shifted.
2. In an acetylene lamp, the combination with the gas generating means, a reflector, and a gas tip extending axially in the reflector, of a holder supported on the reflector adjacent said tip, a serrated bar shiftable through said holder, said holder having a transverse pocket, a cartridge of pyrophoric material within said pocket and engaging said serrated bar, means for pressing said cartridge against said bar, and a finger grip extension at the front end of said bar, said grip extension being in such a position with reference to the tip outlet

that when grasped by the fingers the gas stream will abut against the fingers and be deflected laterally toward the spark stream resulting when said bar is shifted.

3. In an acetylene miner's lamp, the combination with a water container, carbide cup, a reflector at one end of the water container, a gas tube connecting with the carbide cup and extending axially through the reflector wall, and a tip in said tube, of a barrel extending into the water container and projecting through said reflector adjacent said tip, a plug at the front end of said barrel, a serrated bar extending through said plug and into the barrel, a spring within the barrel for resisting outward shift of said bar, said plug having a transverse pocket, a cartridge of pyrophoric material in said pocket, a spring pressing said cartridge against said bar, and a finger grip extension at the outer end of said bar, said grip being in such position with reference to the tip outlet that when grasped by the fingers the gas stream will be projected against the fingers and deflected laterally toward the stream of sparks caused by the shifting of said bar.

In witness whereof, I hereunto subscribe my name this 27th day of August, A. D., 1918.

AUGIE L. HANSEN.
